Primary Examiner — Catherine Ho

(57) CLAIM

The ornamental design for a luggage tag for man, as shown and described.

DESCRIPTION

FIG. 1 is a perspective view of a luggage tag for man showing the new design;

FIG. 2 is another perspective view thereof;

FIG. 3 is a front elevation view thereof;

FIG. 4 is a back elevation view thereof;

FIG. 5 is a left-side view thereof;

FIG. 6 is a right-side view thereof;

FIG. 7 is a top plan view thereof;

FIG. 8 is a bottom plan view thereof; and,

FIG. 9 is a perspective view of the luggage tag for man in an open position.

The broken lines depict portions of the luggage tag for man that form no part of the claimed design.

1 Claim, 9 Drawing Sheets
